UNITED STATES PATENT OFFICE.

HENRY C. MOOERS, OF TOLEDO, OHIO, ASSIGNOR, BY DIRECT AND MESNE ASSIGNMENTS, OF ONE-HALF TO ALANSON WOOD, OF SAME PLACE, AND EDWARD WISNER, OF RICHLAND, LOUISIANA.

MEANS FOR TRANSMITTING MOTION TO SHAFTS AT VARIOUS ANGLES.

SPECIFICATION forming part of Letters Patent No. 612,862, dated October 25, 1898.

Application filed September 15, 1897. Serial No. 651,729. (No model.)

To all whom it may concern:

Be it known that I, HENRY C. MOOERS, of Toledo, county of Lucas, and State of Ohio, have invented certain new and useful Improvements in Means for Transmitting Motion to Shafts at Various Angles; and I do hereby declare that the following is a full, clear, and exact description of the invention, which will enable others skilled in the art to which it appertains to make and use the same, reference being had to the accompanying drawings, and to the figures of reference marked thereon, which form part of this specification.

My invention relates to means for transmitting motion to shafts at various angles, and has for its object to provide a mechanism whereby one or a plurality of shafts may be relatively coupled to a driving-shaft at any angle or angles.

A further object is to eliminate the friction to a minimum by counterbalancing the reciprocating portions of the mechanism.

In the drawings, Figure 1 is a plan view constructed in accordance with my invention. Fig. 2 is a vertical section on lines $\alpha\alpha$. Fig. 3 is an elevation of the journals and casing. Fig. 4 is an isometric view of the reciprocating sleeve. Fig. 5 is a plan view of a counterbalanced disk-crank.

In carrying out my invention I journal in the casing 1 a plurality of shafts 2, radiating from the central point 3. To each of the shafts 2, adjacent to the inner face of the journals 1', are secured disk-crank 4, having secured thereto crank-pins 5. Centrally of the casing 1 and of the different radial shafts a post 6 is secured to the base 7 at right angles to the shafts. Mounted upon post 6 is an oscillating reciprocating sleeve 8, having integral with the body portion 9 projecting lugs 10. Pivotedly secured by suitable means between the lugs 10 are oscillating journals 11, engaging the crank-pins 5. The casing 1 is preferably made in two sections 12 and 13, which are secured at the journals by means of bolts 14, engaging coincident projecting lugs 15, integral with the body of the journal-bearings.

To prevent lateral motion of the shafts 50 within the journal-bearings, a collar 16 is secured to each shaft. The post 6 is secured to the casing-section 12 by suitable means.

17 designates a base-plate properly secured to the casing 1 and is of such form as to allow of its use in various positions. The disk-crank 4 comprise a hub portion 18, having an annular disk 19 integral therewith and in which the crank-pins 5 are secured. Diametrically opposite the crank-pins is a weighted portion 20, integral with the disk, thereby counterbalancing the weight of the crank-pins, oscillating reciprocating sleeve, and oscillating journals pivotally secured thereto.

In the operation of the device either of the 65 shafts may be used as the driving-shaft, the revolution thereof causing the sleeve 8 to reciprocate and oscillate in its reciprocation. The crank-pin journals pivotally secured between the projecting lugs integral with the 70 body of the sleeve 8 are caused to oscillate, and simultaneously with these several movements the crank-pins will reciprocate within the oscillating crank-pin journals, causing the shafts connected to the oscillating reciprocating sleeve to revolve in the same direction 75 as the driving-shaft by the coaction of the connecting mechanism.

It is obvious from the foregoing that the driven shaft or shafts can be revolved at any 80 angle relatively to the intersecting point of the line of the shaft, and I wish it to be understood that I may employ this mechanism to revolve one or a plurality of driven shafts in the same direction as the driving-shaft. 85

What I claim is—

1. In means for transmitting motion to shafts at various angles, a frame, journal-bearings integral with the frame, shafts mounted therein in alinement, a central post secured 90 to the frame at right angles to the shaft, a sleeve mounted thereon, having projecting lugs, boxes pivotally secured between the projecting lugs, crank-pins mounted therein and secured to a crank, and shafts mounted 95 in the journal-boxes and secured to the cranks.

2. In means for transmitting motion to

shafts at various angles, a frame having journal-bearings integral therewith, shafts mounted within said bearings, a post secured to the frame, a reciprocating oscillating sleeve mounted upon the post, lugs integral with the sleeve and projecting therefrom, crank-pin boxes pivotally secured between the lugs, shafts mounted within the journal-bearings of the frame, disk-cranks secured thereon having a counterbalance diametrically opposite and equivalent to the weight of the re-

ciprocating and oscillating mechanism, crank-pins passing into the crank-pin boxes, and a base-plate secured into the frame adapted to secure the device in any position.

In testimony that I claim the foregoing as my own I hereby affix my signature in presence of two witnesses.

HENRY C. MOOERS.
